Patented Oct. 7, 1919.

UNITED STATES PATENT OFFICE.

PETER G. JACOBSON, OF CHICAGO, ILLINOIS.

RAZOR-BLADE HOLDER.

1,318,279.

Specification of Letters Patent.

Patented Oct. 7, 1919.

Application filed August 21, 1917, Serial No. 187,343. Renewed March 6, 1919. Serial No. 281,073.

To all whom it may concern:

Be it known that I, PETER G. JACOBSON, a citizen of the United States, residing at Chicago, in the county of Cook and State of Illinois, have invented a certain new and useful Improvement in Razor-Blade Holders, of which the following is a full, clear, concise, and exact description.

My invention relates to razor blade holders and has for one general object the provision of mechanism whereby the mounting for the handle of the holder, in being moved rearwardly and forwardly, may bring the blade holding jaws into clamping engagement with the blade to be held or may relieve such blade of this clamping action. The jaws are desirably hinged together at their rear ends and the means whereby the handle mounting may be effective in exerting clamping action is desirably inclusive of means for coupling the jaws and mounting in sliding relation, the clamping action being effected when the mounting is moved forwardly and released when the mounting is moved rearwardly.

One of the jaws may be swung apart from the other jaw when the clamping action is released, at which time means is preferably effective to prevent forward movement of the handle mounting.

My invention also has for its object the provision of an "adapter" for application to the holder, this adapter having structural characteristics whereby it may readily be applied to the holder and other characteristics whereby it is suitable to hold the blade of a particular design for which the adapter is made. Thus, if the holder is not adapted readily to hold a given blade directly, such adapter enables the holder readily to hold such blade.

I will explain my invention more fully by reference to the accompanying drawing showing the preferred embodiment thereof
45 and in which Figure 1 is a side view of a razor blade holder constructed in accordance with my invention with a razor blade in position between the jaws of the holder; Fig. 2 is a top view of the structure as it
50 is exhibited in Fig. 1 excepting that a part of the handle is broken away; Fig. 3 is a bottom view of the structure; Fig. 4 is a view on line 4-4 of Fig. 6; Fig. 5 is a view on line 5-5 of Fig. 4; Fig. 6 is a view partially in plan and partially in section on
55

line 6—6 of Fig. 4; Fig. 7 shows the handle mounting drawn to the rear and one of the jaws swung away from the other jaw to permit of the ready insertion of the razor blade; and Fig. 8 is a perspective view 60 of an "adapter" which may be employed, if desired, to hold razor blades of a certain type.

Like parts are indicated by similar characters of reference throughout the different figures. 65

The razor blade holder includes a pair of blade holding jaws 1 and 2. These jaws are in hinged connection at their rear ends whereby the jaw 1 may be swung from and toward the jaw 2. The means by which the jaws 1 and 2 are hinged together desirably resides in a shaft 3 which is in fixed relation with the jaw 1 and in rotatable relation with the jaw 2. The handle mounting is in the form of a hollow block 4 that carries a shaft 5 at its forward end. The handle 6 desirably has its forward end terminating in bifurcations 7 which are coupled with the handle mounting 4 through the agency of the shaft 5, the handle bifurcations 7 and the handle mounting 4 being swingingly connected by means of the shaft 5. The handle mounting 4 is coupled with the jaws

handle mounting 4 is coupled with the jaws 1 and 2 in the manner to permit the handle mounting to move rearwardly and forwardly toward and away from the rear hinged ends of the jaws. To this end the handle mounting 4 is desirably provided with lugs 8 upon that which happens to be the top side thereof, and the lugs 9 upon that which happens to be the bottom side thereof. The lugs 8 pass through the slots 10 provided in and extending longitudinally of the jaw 1. The lugs 9 pass through slots 11 provided in and extending longitudinally of the jaw 2. The lugs 8 and the lugs 9 are bent over at their outer end portions to overlie and underlie the jaws 1 and 2 respectively. When the jaws are in clamping engagement with the razor blade 12 the handle mounting 4 is in its forward position with the lugs 8 and 9 in the forward ends of the slots in the jaws. The overturned outer ends of the lugs 8 and 9, when the mounting 4 is in its forward position, act as clamping means to force the jaws into tight engagement with the blade. The slots 10 in the jaw 1 are desirably provided with angular continuations 10¹ adapted to register with the 110

overturned ends of the lugs 8 and the handle mounting 4 is moved to the rear, it being possible to move this handle mounting to the rear by pulling backwardly upon the handle 6. When the handle mounting is pulled sufficiently to the rear to bring the overturned ends of the lugs 8 into register with the slot continuations 10, the jaw 1 may be swung away from the jaw 2 (Fig. 7) to permit of the ready insertion of a new blade and while the lugs 8 are at the slot enlargements 10¹ the jaw 1 may be closed toward the jaw 2. To prevent the lugs 8 from getting out of alinement with the slot continuations 10¹ while the jaw 1 is opened, that is to prevent the forward movement of the handle mounting 4 while the jaw 1 is opened, said handle mounting is so caught by the shaft 3 (rigidly coupled with the jaw 1) that the handle mounting cannot move forwardly while the jaw 1 is opened. To this end I desirably provide the rear ends of the arms 4¹ that extend rearwardly from and form continuations of the handle mounting 4 with openings 13 adapted to receive the shaft 3. These openings are provided with narrow inlets 14 through which the flattened portions 15 of the shaft 3 may pass when the jaw 1 is closed, at which time the handle mounting 4 may be moved rearwardly or forwardly. When the handle mounting is moved rearwardly to bring the lugs 8 into register with the slot enlargements 10¹ the flat portions 15 of the shaft 3 pass through the inlets 14 into the openings 13 whereafter the jaw 1 may be swung with reference to the jaw 2. When the jaw 1 is swung apart from the jaw 2 the flat portions 15 of the shaft 3 lie across the inlets 14 so that the handle mounting 4 cannot be moved forwardly at this time. When a new blade has been inserted between the jaws the jaw 1 is pressed toward the jaw 2 and the handle mounting 4 is moved forwardly in the position indicated in Figs. 1 to 6 inclusive whereby the jaws are maintained in clamped engagement with the blade.

The razor blade holder illustrated is particularly adapted to hold safety razor blades when they are to be honed, on which account the handle mounting 4 has swinging connection with the handle part 7 through the intermediation of the shaft 5 to allow jaws that are clamped about the blade to be oscillated as the holder is reversed to bring first one side and then the other of the blade into contact with the hone. This oscillation is desirably limited by interengaging formations 16, 17 upon the handle mounting and the handle, the formation 16 being in the nature of a pin projecting through the mounting block while the formations 17 are in the nature of lugs between which the pin moves and which are engaged

by the pin. The rear end of the handle mounting 4 is desirably weighted, sufficient weight being furnished by a roller 18 mounted to turn upon the shaft 3, the roller and the forward edge of the safety razor blade being the only parts that bear upon the hone in the honing operation.

In Fig. 8 I have illustrated in perspective an adapter 19 which is also shown in other views. This adapter is for the purpose of guiding and enabling the ready application of a blade between the jaws of a holder, the adapter being constructed with especial reference to the particular kind of blade to be held and having structural characteristics whereby it is readily adapted for interposition between the jaws of the holder. This adapter has lugs 20 and 21 upon each side thereof. The lugs 20 (Fig. 6) are interposed between the lugs 22 that are carried by the jaw 2 whereby the adapter cannot move sidewise. The forward portion of the adapter engages the lugs 22 to prevent the adapter from moving rearwardly. The lugs 21 upon the adapter engage the rear edges of the lugs 22 to prevent the adapter from being moved outwardly. This adapter carries a spring clip 23 beneath which a blade that is to be sharpened may be slipped. The forward portion of the adapter carries two pilot lugs 24 for reception in the holes of the safety razor blade that is to be sharpened. As the position of the blade with respect to the chapter is determined by the pilot lugs 24 and as the adapter is held with respect to the jaw 2 in the manner described, the blade is consequently held in fixed relation with the jaws when the jaw 1 is clamped closed.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A razor blade holder including a pair of razor blade holding jaws; a handle; a handle mounting with which the handle has swinging connection and movable rearwardly and forwardly; and jaw clamping means operated by the mounting, when moved in one direction, to clamp the jaws upon a blade interposed therebetween, and operated by the mounting, when moved in the reverse direction, to relieve the jaws of clamping action.

2. A razor blade holder including a pair of razor blade holding jaws; a handle; a handle mounting with which the handle has swinging connection and movable rearwardly and forwardly; and means for coupling said jaws and said mounting in slid-

ing relation and serving, when the mounting is moved in one direction, to clamp the jaws upon a blade interposed therebetween, and operated by the mounting, when moved in the reverse direction, to relieve the jaws of clamping action.

5 3. A razor blade holder including a pair of razor blade holding jaws hinged together at their rear ends; a handle; a handle 10 mounting with which the handle has swinging connection and movable rearwardly and forwardly; and jaw clamping means operated by the mounting, when moved in one direction, to clamp the jaws upon a blade 15 interposed therebetween, and operated by the mounting, when moved in the reverse direction, to relieve the jaws of clamping action.

20 4. A razor blade holder including a pair of razor blade holding jaws hinged together at their rear ends; a handle; a handle mounting with which the handle has swinging connection and movable rearwardly and forwardly; and means for coupling said 25 jaws and said mounting in sliding relation and serving, when the mounting is moved in one direction, to clamp the jaws upon a blade interposed therebetween, and operated by the mounting, when moved in the reverse 30 direction, to relieve the jaws of clamping action.

35 5. A razor blade holder including a pair of razor blade holding jaws hinged together at their rear ends; a handle; a handle mounting with which the handle has swinging connection and movable rearwardly and forwardly; and jaw clamping means operated by the mounting, when moved in one direction, to clamp the jaws upon a blade 40 interposed therebetween, and operated by the mounting, when moved in the reverse direction, to relieve the jaws of clamping action, said clamping means and one of said 45 jaws being in separable relation, when the jaws are relieved of clamping action, to permit this jaw to be sufficiently widely separated from the other jaw for the ready insertion of a razor blade between the jaws.

50 6. A razor blade holder including a pair of razor blade holding jaws hinged together at their rear ends; a handle; a handle mounting with which the handle has swinging connection and movable rearwardly and forwardly; and means for coupling said 55 jaws and said mounting in sliding relation, to clamp the jaws upon a blade interposed therebetween, and operated by the mounting, when moved in the reverse direction, to relieve the jaws of clamping action, said 60 coupling, means and one of said jaws being in separable relation when the jaws are relieved of clamping action, to permit this jaw to be sufficiently widely separated from the other jaw for the ready insertion of a 65 razor blade between the jaws.

7. A razor blade holder including a pair of razor blade holding jaws hinged together at their rear ends; a handle; a handle mounting with which the handle has swinging connection and movable rearwardly and forwardly; jaw clamping means operated by the mounting, when moved in one direction, to clamp the jaws upon a blade interposed therebetween, and operated by the mounting, when moved in the reverse direction, to relieve the jaws of clamping action, said 70 clamping means and one of said jaws being in separable relation, when the jaws are relieved of clamping action, to permit this jaw to be sufficiently widely separated from the other jaw for the ready insertion of a razor blade between the jaws; and means governed by the jaw that is adapted for separating movement from its companion for preventing clamping movement of the 85 handle mounting when this jaw is widely separated from the other.

8. A razor blade holder including a pair of razor blade holding jaws hinged together at their rear ends; a handle; a handle 90 mounting with which the handle has swinging connection and movable rearwardly and forwardly; means for coupling said jaws and said mounting in sliding relation, to clamp the jaws upon a blade interposed 95 therebetween, and operated by the mounting, when moved in the reverse direction, to relieve the jaws of clamping action, said coupling means and one of said jaws being in separable relation, when the jaws are relieved of clamping action, to permit this jaw to be sufficiently widely separated from the other jaw for the ready insertion of a razor 100 blade between the jaws; and means governed by the jaw that is adapted for separating movement from its companion for preventing clamping movement of the handle mounting when this jaw is widely separable 105 from the other.

9. A razor blade holder including a pair of razor blade holding jaws hinged together at their rear ends; a handle; a handle mounting with which the handle has swinging connection and movable rearwardly and forwardly; jaw clamping means operated 110 by the mounting, when moved in one direction, to clamp the jaws upon a blade interposed therebetween, and operated by the mounting, when moved in the reverse direction, to relieve the jaws of clamping 115 action; and interengaging formations connected with the handle and handle mounting to limit the relative movement of the handle and its mounting.

10. A razor blade holder including a pair of razor blade holding jaws hinged together at their rear ends; a handle; a handle mounting with which the handle has swinging connection and movable rearwardly and forwardly; means for coupling said jaws 125 130

and said mounting in sliding relation and serving, when the mounting is moved in one direction, to clamp the jaws upon a blade interposed therebetween, and operated by the mounting, when moved in the reverse direction, to relieve the jaws of clamping action; and interengaging formations con-

nected with the handle and handle mounting to limit the relative movement of the handle and its mounting.

In witness whereof, I hereunto subscribe my name this 31st day of July, A. D. 1917.

PETER G. JACOBSON.
